(57) **CLAIM**

The ornamental design for an unplugger nozzle head as shown and described herein.

DESCRIPTION

This application is related to U.S. application Ser. No. 29/887,063, titled “Polisher Nozzle Head”, filed Mar. 16, 2023, which is incorporated herein by reference for all purposes.

FIG. 1 is a front perspective view of an unplugger nozzle head;

FIG. 2 is a rear perspective view of the unplugger nozzle head;

FIG. 3 is a front elevation view of the unplugger nozzle head;

FIG. 4 is a rear elevation view of the unplugger nozzle head;

FIG. 5 is right side view of the unplugger nozzle head;

FIG. 6 is a left side view of the unplugger nozzle head;

FIG. 7 is a top view of the unplugger nozzle head; and,

FIG. 8 is a bottom view of the unplugger nozzle head.

Broken lines shown in the drawings depict portions of the unplugger nozzle head and form no part of the claimed design.

1 Claim, 4 Drawing Sheets
